SPARK CONTROLLING MECHANISM

John R. Rippe, Fresno, Calif.

Application April 21, 1934, Serial No. 721,702

5 Claims. (Cl. 123—148)

My invention relates to means for controlling the timing of ignition sparks in an internal combustion engine, and is particularly concerned with a means for varying the time of occurrence of such sparks.

5 An object of my invention is to provide an automatic means for suitably timing the occurrence of a spark in an engine.

Another object of my invention is to provide 10 means which will afford at least two entirely separate times of ignition in an engine, in response to operating conditions of the engine.

A further object of my invention is to simplify 15 materially the spark timing mechanism of an ignition system.

The foregoing and other objects are attained in the embodiment of the invention shown in the drawing, in which

20 Fig. 1 is a schematic diagram of a controlling mechanism constructed in accordance with my invention and responsive to voltage conditions.

Fig. 2 is a schematic diagram of a modified 25 spark controlling mechanism of my invention, being responsive to oil pressure in the engine.

25 In its preferred form, the spark controlling mechanism of my invention is for use in connection with an engine having an ignition circuit, and includes a spark retard circuit interrupter and a spark advance circuit interrupter either of which 30 is optionally includable in the circuit in response to a condition of the operation of the engine—for instance, in response to oil pressure in the engine lubricating system, or in response to a voltage condition of the engine generator system.

35 In the form of the invention disclosed in Fig. 1, there is an ignition circuit including a source of electricity, such as a battery 6 which at one side is grounded as at 7 and at the other side is connected through an ammeter 8 and a lead 9 to a master switch 10. From the master switch 10 a lead 11 extends to a switch lever 12 which at one end is pivoted to a support 13 by a pin 14 for oscillation between suitable stops 16 and 17. The support is mounted on any suitable base 18 but is electrically insulated therefrom by a non-conducting pad 19. The lever 12 itself is electrically conducting and co-operates with a conductor 21, having a terminal 22, which leads to a spark retard circuit-interrupter lever 23.

40 Lever 23, which is electrically conducting, is pivoted at one end by a pin 24 mounted on a bracket 26 connected through a suitable electric insulator 27 to a support 28. The other end of the lever is provided with a contact 29 adapted to 45 co-operate with a comparable contact 31 mounted

on but electrically insulated from a suitable support 32 and leading to one end of the primary 33 of a suitable ignition coil 34, the other end of the primary being connected to ground as at 36. The secondary 37 of the coil 34 is connected by a lead 5 38 to a conventional distributor 39 from which extend individual circuits 41 leading to spark plugs 42 which finally are connected to ground as at 43.

Somewhat similarly, the lever 12 is adapted 10 also to co-operate with a terminal 46 which is joined by a conductor 47 to an electrically conducting lever 48 one end of which is connected by a pivot 49 to a bracket 51 mounted on but electrically isolated from the support 28 by an 15 insulator 52. The lever 48 likewise carries a contact 53 which is adapted to co-operate with a contact 54 mounted on the electrically insulated base 32 and isolated electrically from the contact 31 by an insulator 56. The contact 54 is 20 connected to one end of the primary 57 of a second ignition coil 58, the other end of the primary being joined to ground, as at 59. The secondary 61 of the coil 58 is connected to the lead 38 and therefore is in electrical communication with the distributor 39 and the various spark plugs 42. The contacts 53 and 54 as well as the contacts 25 29 and 31 can be bridged by condensers, not shown, in the usual way.

In order that the lever 23 will be effective to 30 operate the contacts 29 and 31 to interrupt the circuit to produce a relatively retarded spark, there is provided on the lever 23 an electrically insulating abutment 62 which in effect is a cam follower operating against a multi-lobed cam 63 35 mounted to rotate in the direction of the arrow 64 in time with the operation of the engine to which the system pertains. The position of the abutment 62 with respect to the cam 63 is such that the contacts 29 and 31 are separated to produce a so-called retarded spark in the spark plugs 42. 40

The lever 48 is likewise provided with an electrically insulating projection 66 which is so located, however, as to be contacted by the lobes 45 of the cam 63 at such a time in the rotation of the shaft as to produce a so-called advanced spark, by separation of the points 53 and 54. Thus, when the points 29 and 31 are in circuit 50 there is a retarded spark at the spark plugs 42, while when the contacts or interrupters 53 and 54 are in circuit an advanced spark is produced at the spark plugs 42. Of course, the precise timing is adjustable in accordance with usual 55 practice.

I utilize either one of the pair of interrupters in accordance with any selected condition which occurs in the engine to which the system pertains. The engine is provided with a suitable generator 5 67, one side of which is connected to ground by a lead 68 and the other side of which is connected by a lead 69 to a voltage cut-out 71 of a standard kind. The function of the cut-out is to remain open when the generator 67 is rotating so slowly 10 as to produce only a relatively low voltage, while the cut-out 71 automatically closes and incorporates the generator 67 in a charging circuit when the voltage rises to and above a predetermined value which depends upon the speed of operation 15 of the generator and correspondingly of the engine.

The cut-out 71, when closed, includes the grounded generator in circuit by a lead 72 which extends to a solenoid 73 connected through a lead 20 74 to the lead 8 and thence through the ammeter 8 and battery 6 to ground. The solenoid 73 is provided with a plunger 76 which is connected to but insulated from the lever 12, and the attraction of the solenoid when energized is opposed by an 25 insulated coil spring 77. The spring normally urges the lever 12 against the stop 16 and with the interrupters 29 and 31 in the ignition circuit to produce a retarded spark. When the speed of the engine increases sufficiently so that the voltage 30 generated by the generator 67 is ample to close the cut-out and to put the generator in circuit with the battery 6, then the solenoid 73 is simultaneously and correspondingly effective to pull the plunger 76 into the solenoid, overcoming 35 the urgency of the spring 77 and moving the lever 12 so that the terminal 46 is electrically connected with the lever and the terminal 22 is electrically disconnected therefrom. This action occurs abruptly so that the interrupter 29, 31 is 40 abruptly cut out of the circuit while the interrupter 53, 54 is abruptly and simultaneously introduced into the circuit.

The ignition spark timing, therefore, is altered from retarded condition to advanced condition 45 abruptly at the proper point in the operation of the engine, dependent upon the speed of operation thereof. The reverse change occurs as the engine slows down and the voltage of the electricity supplied by the generator 67 is reduced 50 below the critical value. Then the cut-out 71 opens and the solenoid 73, being therefore de-energized, permits the spring 77 to return the lever 12 to the position shown in Fig. 1, thereby returning the contacts 29 and 31 to their active 55 condition in the circuit and removing the interrupters 53 and 54 from actively affecting the circuit. The ignition spark is then in retarded condition.

As indicated in Fig. 2, there is another condition 60 which is responsive to engine speed and somewhat to engine load, which can be utilized in place of the electrical voltage. In this arrangement, which in many respects is comparable with the arrangement previously described, and in which 65 identical reference numerals indicate identical parts, the voltage cut-out 71 is directly connected to the ammeter 8 by a lead 81; but in order to move the lever 12 there is utilized the pressure developed by a lubricating oil pump 82 which is 70 connected to the engine to which the system pertains and which operates in accordance with the load thereon.

The pump 82 is connected through a pressure pipe 83 to an expansible bellows 84 which in turn 75 is connected by a rod 86 and an electrically in-

sulating pivotal joint 87 to an extension 88 on the lever 12. When the pressure developed by the operation of the pump 82 is below a critical value, the bellows 84 is incapable of overcoming the bias or urgency of the spring 77, which may be 5 adjusted or set at any desired value, and the spark remains in a retarded condition. Nevertheless, when the pump 82 is effective to raise the pressure in the bellows above a predetermined value, then such bellows is effective abruptly to 10 overcome the urgency of the spring 77 and to move the lever 12 from its position in conjunction with the terminal 22 into a position in conjunction with the terminal 46, so that the spark is 15 abruptly changed at the critical pressure existing in the bellows and corresponding to a critical speed and load of the engine, from its retarded condition to its advanced condition.

The reverse action occurs when the speed of the engine decreases below a critical point and 20 the pressure exerted upon the bellows 84 by the pump 82 drops below a critical value. At such time the urgency of the spring 77 is ample to overcome the counter-urgency of the bellows 84 exerted through the rod 86, and the lever 12 is returned from its position in conjunction with the terminal 46 to its position in conjunction with the terminal 22, thereby restoring the spark from its advanced condition to its retarded condition. 25

In accordance with my invention, therefore, 30 there is provided means responsive to a condition, such as speed and load of the engine, which is effective to alter the ignition spark from a retarded condition to an advanced condition, and vice versa. 35

I claim:

1. A spark controlling mechanism comprising an engine ignition circuit, a retarded spark circuit interrupter, an advanced spark circuit interrupter, a switch for alternatively including either one of said interrupters in said circuit, and means responsive to a critical speed of said engine for abruptly actuating said switch to include said advanced spark circuit interrupter in said circuit and to exclude said retarded spark circuit interrupter from said circuit. 40

2. A spark controlling mechanism comprising an engine ignition circuit, a first circuit interrupter, a first induction mechanism operating in conjunction with said first circuit interrupter, a second circuit interrupter, a second induction mechanism inductively isolated from said first induction mechanism and operating in conjunction with said second circuit interrupter, and means responsive to a critical speed of said engine for abruptly including one of said circuit interrupters and its associated induction mechanism in said circuit and excluding the other of said circuit interrupters and its associated induction mechanism therefrom. 50

3. A spark controlling mechanism comprising an engine ignition circuit; a retarded spark circuit interrupter; a first induction coil including a primary winding, a core, and a secondary winding adapted to be controlled by said retarded spark interrupter; an advanced spark circuit interrupter; a second induction coil including a primary winding, a core, and a secondary winding adapted to be controlled by said advanced spark interrupter; a switch for alternatively including either one of said interrupters and the primary winding of the associated one of said coils in said circuit and excluding the other of said interrupters and the primary winding of the other one of said coils from said circuit, and 60

35

45

55

60

70

75

means responsive to the operation of the engine to which said circuit pertains for operating said switch.

4. A spark controlling mechanism comprising an engine ignition circuit, a retarded spark circuit interrupter, a first induction coil having its primary winding connected to said retarded spark circuit interrupter, an advanced spark circuit interrupter, a second induction coil having its primary winding connected to said advanced spark circuit interrupter, a switch for alternatively including either one of said interrupters and its respective induction coil in said circuit, means for urging said switch to include said retarded spark circuit interrupter and said first coil in said circuit and to exclude said advanced spark circuit interrupter and said second coil from said circuit, and means responsive to an increase in the speed of operation of the engine to which said circuit pertains for overcoming the urgency of said means to include said

advanced spark circuit interrupter and said second coil in said circuit and to exclude said retarded spark circuit interrupter and said first coil from said circuit.

5. A spark controlling mechanism comprising an engine ignition circuit, a retarded spark circuit interrupter, an advanced spark circuit interrupter, a pair of inductively isolated induction coil primary windings one for each of said interrupters, a switch for alternatively including either one of said interrupters and its respective primary winding in said circuit, and means responsive to a critical speed of said engine for abruptly actuating said switch to include said advanced spark circuit interrupter and its respective primary winding in said circuit and to exclude said retarded spark circuit interrupter and its respective primary winding from said circuit.
